UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

PNEUMATIC CORE-WIRE PULLER.

1,343,701.

Specification of Letters Patent. Patented June 15, 1920.

Application filed December 3, 1918. Serial No. 265,134.

To all whom it may concern:

Be it known that I, BURTON S. AIKMAN, a citizen of the United States, residing at Milwaukee, in the county of Milwaukee and 5 State of Wisconsin, have invented new and useful Improvements in Pneumatic Core-Wire Pullers, of which the following is a specification.

This invention relates to devices for pulling core wires out of castings, and the principal object of my invention is to provide a fluid pressure operated machine for the above purpose.

Heretofore, core wires have been drawn 10 from castings manually, which process is very slow and tedious and often requires considerable physical effort.

Furthermore, it is sometimes physically impossible for the operator to pull the core 15 wire out by a straight pull, with the result that the core wires are often twisted and broken, so that the wires cannot be used again.

By employing a machine in accordance 20 with my invention, very little physical effort is required to draw the core wires, the rapidity of operation is greatly increased, and the wires are pulled straight, so that a much greater percentage of the wires can be used again.

In the accompanying drawing; Figure 1 is a sectional view of a core wire pulling machine constructed in accordance with my invention; Fig. 2 an end view thereof; and 25 Fig. 3 a part sectional view of a casting containing core wires, showing how the clamping jaws of the core wire pulling machine take hold of the core wires.

According to the construction shown in 30 the drawing, the machine may comprise a main pulling cylinder 1, containing a piston 2 having a piston stem 3, which projects rearwardly through a cylinder cup 4.

Pull rods 5 are mounted on opposite sides 35 of the cylinder 1 and are secured to a cross head 6 carried by the rear end of the piston stem 3. The pull rods 5 extend forwardly beyond the cylinder 1 and at the forward ends have a fixed clamping jaw 7 secured thereto and therebetween.

A movable clamping jaw 7 is pivotally mounted on the fixed jaw 6 and is adapted 40 to be operated by an arm 8 pivotally secured to a piston stem 9 of a piston 10 contained 5 in a clamping cylinder 11.

The cylinder 11 is secured to brackets 12 which in turn are secured to the pull rods 5, so that the clamping cylinder moves with said rods.

Extending vertically on opposite sides of 60 the clamping jaws 6 and 7 are yokes 13, which are secured to the pressure head of cylinder 1 and serve to hold the casting against rearward movement while the core wires are being pulled. Said yokes may be 65 braced apart by means of a crossbar 14, secured thereto.

Fluid under pressure is supplied to piston 10 through a pipe 15, a pipe 16, and a flexible hose 17, which permits movement of 70 the cylinder 11, and the supply of fluid to pipe 15 from a source of fluid supply pipe 18 may be controlled by a valve 19 adapted to be operated by a foot treadle 20.

The supply of fluid under pressure to the 75 main pulling piston 2 is controlled by a valve 21 adapted to be operated by a diaphragm 22, subject on one side to fluid pressure supplied to pipe 16 and on the opposite side to the pressure of a spring 23.

In operation, a casting containing core 80 wires, such as the casting 24 shown in Fig. 3 is applied to the machine, so that the exposed ends of the core wires 25 rest on top of the fixed jaw 6.

The treadle 20 is then depressed, so as to open valve 19 and permit the flow of fluid from pipe 18 to pipe 15 and thence through pipe 16 and the flexible hose 17 to cylinder 11.

The piston 10 is then moved forwardly, causing the jaw 7 to firmly clamp the core wires 25. When the fluid pressure in pipe 16 has reached a predetermined degree, sufficient to give the desired clamping pressure 95 on the core wires, through the action of piston 10, the diaphragm 22 is adapted to be operated by the fluid pressure in said pipe, so as to open the valve 21 and permit the flow of fluid through pipe 26 to the 100 piston 2. Said piston is thereupon shifted rearwardly, causing the rearward movement of the pull rods 5 and the clamping jaws. The casting 24 is held against rearward movement by engagement with the yokes 13, 105 so that the clamping jaws operate to pull the core wires 25 out of the casting.

When the core wires have been pulled, the parts are returned to normal position by permitting the valve 19 to close, at the same 110

time opening an atmospheric vent from pipe 15 around the stem 27 of valve 19.

Fluid is thus released from piston 10 and also from piston 2 through pipe 28, containing a check valve 29, for preventing flow of fluid from pipe 15 to pipe 28. The pistons 2 and 10 are then returned to release position by their respective springs 30 and 31 and the core wires are released from the clamping jaws.

Pressure gages 32 and 33 may be connected to the cylinders 11 and 1, so that the fluid pressure attained in the cylinders may be noted when desired.

Having now described my invention, what I claim as new, and desire to secure by Letters Patent is:—

1. In a core wire pulling machine, the combination with a cylinder, a piston therein operated by fluid under pressure for supplying power for pulling the core wires, and clamping jaws movable by said piston and adapted to grip the core wires, of a second cylinder and a piston therein, operated by fluid under pressure, for actuating said jaws, and means for first supplying fluid under pressure to the second cylinder and then automatically to the first cylinder.

2. In a core wire pulling machine, the combination with a cylinder, a piston there-

in operated by fluid under pressure for supplying power for pulling the core wires, and means for gripping the wires, of a second cylinder, a piston therein, operated by fluid under pressure for actuating said means, and means operated at a predetermined fluid pressure in the second cylinder for supplying fluid under pressure to the first cylinder.

3. In a core wire pulling machine, the combination with a cylinder, a piston therein operated by fluid under pressure for supplying power for pulling the core wires, of a yoke movable with said piston, a second cylinder mounted on said yoke, a piston therein operated by fluid under pressure, and means operated by said piston for gripping the core wires.

4. In a core wire pulling machine, the combination with clamping jaws for gripping the core wires in a casting, a cylinder, a piston therein for operating said jaws to pull the core wires, a second cylinder, and a piston therein for operating said jaws to grip the core wires, of stop members for resisting movement of the casting upon pulling the core wires therefrom.

In testimony whereof I have hereunto set my hand.

BURTON S. AIKMAN.
